FOUNTAIN BRUSH WITH CLOSURE CAP CONTROLLED VALVE

Frederick R. Wittnebert, Chicago, Ill., assignor to Dupli-Color Products Company, Inc., Chicago, Ill., a corporation of Illinois

Application July 8, 1953, Serial No. 366,798

9 Claims. (Cl. 15—139)

This invention relates to a fountain applicator and more particularly to a fountain brush.

An object of this invention is to provide an improved and simplified form of fountain applicator or brush especially adapted for use in applying lacquers on walls and the like and for covering scratches, mars, etc. on metal, wood, or unfinished surfaces of other materials.

Still another object of this invention is to provide a fountain applicator of the type having a closure cap and wherein the cap is utilized to maintain the fluid control valve of the applicator open when the cap is on the applicator body or reservoir.

In accordance with the general features of this invention there is provided a fountain applicator comprising a fluid containing reservoir, a bristle brush at one end thereof, resiliently urged means controlling flow of fluid from the reservoir to the brush, and a closure cap for the brush end of the reservoir guided on the reservoir to direct an internal projection into the brush to depress and open the means whereby fluid flows to the brush when the cap is on the reservoir end.

Another feature of the invention relates to the provision of an agitator in the reservoir of the applicator movable to stir the fluid entirely independent of the valve control means.

Other objects and features of this invention may more fully appear from the following detailed description taken in connection with the accompanying drawings which illustrate several embodiments thereof and in which

Figure 1 is a side elevation of my novel applicator;

Figure 2 is an enlarged vertical cross sectional view through the applicator partly broken away and showing the cap in closure position on the applicator reservoir;

Figure 3 is an enlarged fragmentary cross-sectional view similar to Figure 2 showing the ejected position of the bristle brush when the cap is removed;

Figure 4 is a cross-sectional view taken on the line IV—IV of Figure 2 looking downward;

Figure 5 is a fragmentary cross-sectional view similar to Figure 3 showing a modified form of applicator; and

Figure 6 is a cross-sectional view taken on the line VI—VI of Figure 5 looking downward.

As shown on the drawings:

The reference character 10 designates generally a fluid containing reservoir or barrel closed at one end 11 and having an external thread 12 at the other end to receive detachably and sealingly a closure cap 13.

More specifically, the reservoir 10 includes a cylindrical shell or casing 15 made of metal, synthetic plastic or the like having suitably secured in its open end a tubular plug 16 which carries a thread 12. The plug 16 has a reduced diameter nozzle end projecting from the shell 15 and providing a shoulder 17 adjacent the threads 12.

Disposed inside of the bore 18 of the plug or insert 16 is a helical compression spring 19, one end of which abuts a washer 20 press fitted into a countersunk opening

2

21 at one end of the bore 18. The other end of the spring 19 abuts a guide washer 22 carried on an annular enlargement or shoulder 23 of a brush stem 25.

Both the washers 20 and 22 may be made of any suitable material, such, for example, as a synthetic plastic. Each of them has a central opening of larger diameter than that of the stem proper so that the stem loosely passes through these washers. It will also be noted from Figure 4 that the washer 22 has cut away or flat portions 26 spaced from the wall of the tubular plug 16 so that fluid in the upper part of the reservoir 10 can flow between the edges of this washer 22 and the inside wall of the plug 16 while the washer still acts as a guide for the stem 25.

The enlarged or shouldered end 23 of the stem 25 is cupped, as indicated at 27 in Figure 3, and has embedded in it the base 28 of a bristle brush 30.

It will also be noted that the external or free end of the tubular plug 16 is reduced and rounded at 31 and has a reduced opening 32 comprising the valve opening of the applicator. This opening 32 is of such a size, as shown in Figure 3, that the brush base 28 can loosely telescope the same when the applicator stem 25 is in closed position. When in this position the lower edge of the shouldered end 23 of the stem contacts at 33 the interior wall of the open end 31 of the applicator to form a valve for metering or shutting off the flow of fluid from the reservoir or barrel 11 to the bristles of brush 30. The shouldered end 23 of the stem 25 is maintained in this closed position under the resilient pressure of the compression spring 19.

Also disposed in the barrel 11 of the reservoir 10 is an annular weight 35 which is between the plug 16 and the closed end of the reservoir. It is movable in the barrel or casing 11 entirely independent of the movement of the stem 25, which stem is free to move through the center of the weight as shown in Figure 2.

The weight is effective as an agitator for stirring up the fluid in the reservoir by simply shaking the fountain reservoir or by turning it upside-down.

My invention is especially concerned with the coaction of the cap 13 with the bristle brush 30 or more specifically with the valve stem 25. As shown in Figure 2, the cap has embedded in the inside surface of its closed end, a pointed metal pin 40 depending centrally in the cap to terminate within the cap. The pin is of such length that the cap will be guided by the nozzle to align the pin longitudinally so that it will centrally penetrate the bristles of brush 30 and strike the brush base 28 for raising the valve shoulder 23 out of valve closing position.

In other words, the cap 13 is placed on the nozzle, guided by its side wall on the side wall of the nozzle to align the pin with the brush and as the cap is screwed onto the threads 12, the pin 40 penetrates the bristles of brush 30, impinging against the valve or stem enlargement 23 and moving it from the closed valve position shown in Figure 3 to the open position shown in Figure 2. When in this latter position, the fluid in the reservoir can freely flow downwardly around the bristles of the brush 30 which has been pushed back into the open end 31 of the plug 16.

The tip 41 of the open end of the plug end 31 is adapted, when the cap is on the reservoir, to sealingly engage a synthetic plastic insert 42 or washer embedded in the cap around the pin 40. This seal serves to minimize evaporation of the fluid around and in the bristles of brush 30 and yet enables the bristles to be maintained and kept moist by the fluid.

In Figures 5 and 6 I have illustrated a modification of the invention wherein the parts common to these figures and Figure 3 are, for purposes of simplicity, given the

same reference characters. Actually, the only difference resides in the construction of the enlarged end 23' of the stem 25'. In this form the spacing guide or washer 22' is formed integral with the stem enlarged end 23'. This guide 22' has spaced radial ears or lugs 26' for contacting the inside surface of the reservoir plug 16. Also, the bristles of brush 30' are embedded directly in the lower integral end 28' of the enlargement or shoulder 23'. Otherwise, this form of the invention is the same and operates in the same manner as the first described embodiment.

As illustrated in Figures 3 and 5 when the brush is projected beyond the nozzle end 31, the spring holds the valve on the tapered seat to stop flow to the brush. When sufficient end load is placed on the brush it will 15 retract into the bore to unseat the valve and permit flow of fluid to the brush. This flow will be controlled or metered by the valve in accordance with the spacing of the valve from the seat. Thus the end load on the brush will not only control the distance which the bristles project 20 but will also control the degree of valve opening to modulate fluid flow to the brush.

I claim as my invention:

1. A fountain applicator comprising a reservoir with an elongated side wall portion, a pin penetrable applicator at one end thereof, resiliently urged modulating valve means supporting said applicator and controlling flow of fluid from the reservoir to the applicator while metering said flow when open and substantially stopping flow when closed, guide means in the reservoir slidably supporting the valve means while accommodating relatively free flow of fluid between the valve and reservoir, said applicator upon application of end load thereto being retractable into the reservoir under control of said guide means to open the valve and receive fluid from the reservoir, a closure cap for the applicator end of the reservoir having an end wall for sealing the applicator end of the reservoir, an elongated side wall for engaging the side wall portion of the reservoir to direct the cap into coaxial alignment with the reservoir before the end wall contacts the projected applicator and an internally threaded open end beyond said side wall, a relatively thin elongated pin in said closure cap depending from said end wall centrally of the cap and terminating inwardly from the open end of the cap to be aligned with the applicator by the guiding of the elongated side wall of the cap on the reservoir before engaging the valve means, said pin being sufficiently long to penetrate the applicator and depress the valve means into the reservoir in advance of the end wall of the cap while the valve means is still under control of said guide means for the valve means whereby the valve will be opened and the applicator will be submerged in fluid contained in the reservoir, and a thread on the reservoir mating with the threaded cap portion to draw the end wall of the cap into tight sealing relation with the reservoir.

2. A fountain applicator comprising a tube having a dispensing orifice, a flow control valve slidably guided in the central portion of the tube to receive fluid therearound when open and to substantially stop flow when closed, a brush on said valve being sufficiently stiff to fit freely through the orifice and to project beyond the tube, said brush adapted to be depressed upon application of end load thereon to open the valve for receiving fluid from the tube, a closure cap for the tube having an elongated side wall guided on the tube and an end wall for overlying the tube in sealed relation therewith, an elongated relatively thin pin depending from said end wall centrally of the cap and terminating inside the cap, said side wall of the cap being longer than the projected length of the brush sufficiently for engaging the side wall of the tube to longitudinally align the pin with the central portion of the orifice before the pin engages the valve, said side wall of the cap and tube cooperating to direct the pin longitudinally through the brush and

against the valve, said pin being sufficiently long to depress the valve for holding the applicator in advance of the end wall of the cap, and coacting means on the cap and tube to hold the cap in sealed engagement over the end of the tube with the pin retracting the brush into the tube and opening the valve to submerge the brush in the contents of the tube.

3. A fountain applicator comprising a fluid containing reservoir having a dispensing nozzle with an internal valve seat adjacent the outlet end thereof, a pin penetratable applicator carrying flow modulating valve slidably mounted in the longitudinal central portion of the nozzle and adapted to receive fluid from the reservoir therearound, a spring in the nozzle urging the valve toward said seat to close the outlet end of the nozzle and to project the applicator beyond the nozzle, said applicator fitting freely in said outlet end of the nozzle and said spring adapted to be compressed by end load on the applicator to accommodate unseating of the valve and controlled flow from the reservoir to the projected applicator, and a removable screw cap for said nozzle having an elongated side wall guided on the nozzle, said cap having a centrally depending relatively thin internal pin terminating inwardly from the open end of the cap, the relative lengths of the side wall of the cap and the pin being such that the pin is positioned by the cap as it is guided on the reservoir into longitudinal alignment with the applicator for penetrating the applicator and engaging the central portion of the valve to depress the valve for holding the applicator in advance of the end wall of the cap, and a screw thread on said nozzle coacting with the screw cap to draw the cap tightly against the outlet end of the nozzle to seal the nozzle while holding the applicator inside the nozzle in submerged relation with fluid in the reservoir.

4. A valved fountain brush which comprises a closed bottom open top container, a tubular plug secured in the open end of the container and projecting therefrom to provide an elongated side wall and an apertured end remote from the container, said plug having a bore therethrough and a valve seat adjacent the apertured end of the plug, a stem slidably guided in the center of the plug bore adapted to receive fluid from the container freely therearound, a flow modulating valve on said stem coacting with said seat to selectively stop and to control flow from the bore through the aperture, a spring on said stem urging the valve against said seat, a closure cap having an open end, an elongated side wall for embracing said side wall of the plug and an end wall for overlying the apertured end of the plug, a relatively thin pin depending longitudinally from said end wall in the center of the cap and terminating inwardly from the open end of the cap, brush bristles carried by the valve adapted to fit freely through the plug aperture to project beyond the plug when the valve is seated on the valve seat, the relative lengths of the pin and side wall of the cap being such that said elongated side wall of the plug directs the side wall of the cap to align the pin longitudinally with the central portion of the aperture for penetrating the brush and engaging the valve in the aperture to depress the valve for holding the brush in advance of the end wall of the cap, coacting means on the cap and plug to secure the cap on the plug with its end wall sealing the plug aperture and its pin penetrating the brush bristles to engage the valve for retracting the brush bristles within the plug bore in communication with the contents of the container whereby fluid in the container can flow freely around the stem and valve to submerge the brush bristles.

5. A fountain applicator comprising a closed bottom open top cylindrical shell, a longitudinally bored tubular plug in said open end of the shell having a reduced diameter nozzle portion projecting beyond the shell with a rounded apertured end, said plug having a bore therethrough with a valve seat portion converging to said end,

a counterbore in the large end of the plug, a stem in said bore and counterbore having a valve thereon coating with said seat to control flow through the aperture, circumferentially spaced lugs projecting from said valve in free sliding relation with the bore wall, a washer press fitted in said counterbore freely receiving the stem therethrough and coacting with the lugs to guide the stem and valve in the longitudinal central portion of the bore while accommodating flow of fluid from the shell therearound, a spring around the stem compressed between the washer and valve to urge the valve against the seat, brush bristles carried by the valve and projecting therefrom freely through the aperture, a cap for said nozzle having an elongated side wall guided on said nozzle and an end wall for overlying the apertured end of the nozzle in sealed engagement therewith, a pin depending centrally in the cap from the closed end and terminating within the cap, the relative lengths of the side wall and pin being such that said nozzle guides the side wall of the cap to direct the pin through the brush bristles and centrally against the valve to depress the brush into the bore in advance of the end wall of the cap and open the valve for free flow of fluid in the nozzle over the brush, coacting means on the plug and cap to draw the cap tightly against the end of the nozzle, and a tubular weight freely slideable in the shell receiving the stem therein and bottomed by the plug to agitate the contents of the shell and direct the same through the washer when the applicator is shaken.

6. A fluid applicator comprising an elongated barrel having a closed bottom and a reduced diameter elongated nozzle projecting from the top thereof, said nozzle having a longitudinal bore therethrough in communication with the barrel and a valve seat converging from the bore to a reduced diameter opening through the end of the nozzle, a stem in the central portion of said nozzle having a flow modulating valve coacting with said seat to substantially stop flow when seated, brush bristles carried by said valve and projecting freely through said opening in the end of the nozzle, spaced opposed guide means in said bore coacting with said stem, one of said guide means being secured to the nozzle, the other of said guide means being movable with the stem, a spring between said guide means urging the valve against its seat while projecting the bristles beyond the nozzle, said spring adapted to be compressed upon application of end load to said bristles for partially retracting the bristles into the nozzle to open the valve and meter flow to the bristles, an end cap having an elongated side wall for slidably embracing said nozzle to longitudinally align the cap on the nozzle, said cap having an end wall for sealing the open end of the nozzle, an internal pin depending from the end wall of the cap and terminating inwardly from the mouth of the cap, said side wall of the cap being sufficiently long that when the cap slidably embraces said nozzle the pin will be automatically aligned with the central portion of the opening through the end of the nozzle before the pin engages the valve on the seat adjacent said opening whereby the pin will penetrate the brush bristles and engage the valve for opening the valve while depressing the brush bristles into full communication with fluid in the reservoir to submerge the brush bristles in said fluid when the cap seals the end of the nozzle.

7. A fountain applicator comprising a reservoir for fluid having a dispensing outlet, with an elongated outer side wall, a valve in the outlet selectively controlling and stopping flow through said outlet, a pin penetratable applicator carried by said valve adapted to be selectively projected beyond the outlet and retracted into the outlet, a closure cap for the outlet having an open end, an elongated inner side wall extending from said open end for surrounding said outer side wall of the reservoir to be guided by the outer side wall into fitted engagement with the reservoir and an end wall for covering the outlet in

sealed relation when the cap is fitted on the reservoir, a relatively thin pin longer than the projected length of the applicator depending from said end wall longitudinally inside said cap and terminating in spaced relation inwardly from the open end of the cap, said pin adapted to penetrate the applicator and project freely through the dispensing outlet to thrust against the valve for retracting the applicator and valve into the reservoir, and the inner side wall of the cap being sufficiently longer than the pin for coacting with the outer side wall of the reservoir to align the pin longitudinally with the applicator and with the central portion of the opening before the pin penetrates said applicator and thrusts against the valve to exert a retracting force whereby the pin will not damage the applicator even when the cap is rotated.

8. A fountain applicator comprising a tube having a dispensing orifice at one end, a flow control valve in the tube and movable along the central axis thereof to receive fluid therearound to meter flow when open and to substantially stop flow when closed, a pin penetratable applicator on said valve adapted to fit freely through the orifice and to project beyond the tube, said applicator being sufficiently stiff to be depressed upon application of end load thereon to open the valve for receiving fluid from the tube, a closure cap for the tube having an elongated side wall guided on the tube and an end wall for overlying the tube in sealed relation therewith, an elongated relatively thin pin in the cap extending from said end wall along the central axis of the cap and terminating inside the cap, said side wall of the cap being longer than the projected length of the applicator sufficiently for engaging the side wall of the tube to longitudinally align the pin with the central portion of the orifice before the pin engages the valve, said side walls of the cap and tube cooperating to direct the pin longitudinally through the applicator and against the valve, said pin being sufficiently long to depress the valve for holding the applicator in advance of the end wall of the cap and with the pin retracting the applicator into the tube and opening the valve to submerge the applicator in the contents of the tube.

9. A fountain applicator comprising a reservoir-defining elongated body having a dispensing orifice at one end and a valve seat inside said body adjacent the orifice, a spring-loaded valve within said body coacting with said seat to selectively control and stop flow to the orifice from said reservoir, a pin-penetrable applicator on said valve adapted to project through and beyond said orifice, said applicator being sufficiently stiff to be depressed upon application of end load thereon to move the valve off of said seat and open the reservoir to the orifice for modulated controlled flow from the reservoir to the applicator, a closure cap for the applicator having an end wall for sealing engagement with the orifice end of the body to seal the orifice, an elongated side wall for engaging the body to direct the cap into aligned relation with the body, and an elongated relatively thin pin projecting from said end wall centrally of the cap and terminating inwardly from the open end of the cap to be aligned with the applicator by the guiding of the side wall of the cap on the body before engaging the valve, said pin being sufficiently long to penetrate the applicator and depress the valve off of its seat with the applicator in advance of the end wall of the cap to immerse the applicator in the contents of the reservoir during periods of non-use while simultaneously engaging the end wall of the cap with the body around the orifice to seal the applicator in the body.
